UNITED STATES PATENT OFFICE.

RANDOLPH R. BUETO, OF SLAUGHTER, LOUISIANA.

FENCE-POST.

No. 833,577.

Specification of Letters Patent.

Patented Oct. 16, 1906.

Application filed June 16, 1906. Serial No. 322,110.

To all whom it may concern.

Be it known that I, RANDOLPH R. BUETO, a citizen of the United States, and a resident of Slaughter, in the parish of East Feliciana and State of Louisiana, have made an Improvement in Fence-Posts, of which the following is a specification.

My invention is an improvement in the class of metallic fence-posts which are provided with means for anchoring them in the ground.

The invention is embodied in the construction, arrangement, and combination of parts hereinafter described, and illustrated in the accompanying drawings, in which—

Figure 1 is a perspective view of my fence-post and the means for anchoring the same in the ground. Fig. 2 is a central longitudinal section of the post and the means for anchoring the same in the ground, a wire fastening being shown in side view.

A indicates a tubular iron post, and B an iron anchoring-plate having a central hole in which the post is inserted, the same projecting a considerable distance into the ground, as indicated in Fig. 2. The plate B is preferably rectangular, and its ends b are bent downward and enter the ground, the body of the plate lying upon the top of the ground or being but slightly embedded in it. The post is provided with a collar a, which rests directly upon the anchor-plate B and supports it thereon, the post being easily detachable from the plate B, yet firmly supported when in use. The collar is secured by shrinking it on the post or by any other means which may be preferred.

The post is provided with a series of lengthwise slots a' on one side and with opposite holes a² on the other side. In practice there are as many series of such slots and holes as there are wires C, and it will be understood that the slots are necessarily in alinement, as well as the holes a².

The wire fastenings consist of a screw-bolt D, having one end bent to form a hook d, the same being arranged at an acute angle to the body of the bolt to adapt it to hold a wire. The slots a' in the post A are adapted to re-

ceive the head of the bolt, which is provided with the inclined hook or prong d, and the holes a² are similarly adapted to receive the threaded cylindrical end of the bolts. A nut d' is applied to the threaded end of each bolt exterior to the post, as shown in Fig. 2.

I claim—

1. An improved fence-post and means for anchoring it in the ground, the same comprising the post proper and the anchoring-plate having pendent flanges adapted to enter the ground, the post passing through the plate and projecting a considerable distance below it, and being provided with a fixed collar that rests upon the upper side of the plate, substantially as described.

2. The combination with an anchoring-plate adapted to rest upon the ground and having flanges for entering the same, of a post which passes through a hole in the center of the plate and projects a considerable distance below it, the post being provided with a fixed collar that rests upon the plate, the post and plate being readily detachable, substantially as described.

3. The improvement in fence-posts herein described, comprising a base or anchor plate having a central opening and provided at its opposite ends with flanges bent down at a right angle to enter the ground, and made of a uniform width throughout their lengths whereby the flat edges at the lower ends of the flanges are provided to prevent any rocking or tilting of the plate in the ground, and the post proper fitting at its lower end within the opening in the plate and extending below the plate a considerable distance and to a point below the lower edges of the end flanges and provided above the said plate with an annular collar bearing uniformly upon the base-plate to swing the central opening therein and coöperating with the flat-edged end flanges in preventing any rocking of the plate when in the ground, substantially as set forth.

RANDOLPH R. BUETO.
